DESIGN FOR A PLAY SUIT

Margit Fellegi Laszlo, Los Angeles, Calif., assignor to Cole of California, Inc., a corporation of California

Application March 25, 1947, Serial No. 137,876

Term of patent 7 years

(Cl. D3—17)

To all whom it may concern:

Be it known that I, Margit Fellegi Laszlo, a citizen of the United States, and a resident of Los Angeles, California, have invented a new, original, and ornamental Design for a Play Suit, of which the following is a specification, reference being had to the accompanying drawing, forming part thereof.

Referring to the drawing:

I claim:

The ornamental design for a play suit, as shown.

MARGIT FELLEGI LASZLO.
